UNITED STATES PATENT OFFICE.

OLE J. BORGE, OF DAVIS TOWNSHIP, KITTSON COUNTY, MINNESOTA.

RIVET-FEEDING MECHANISM.

1,132,826.

Specification of Letters Patent. Patented Mar. 23, 1915.

Application filed June 22, 1914. Serial No. 846,662.

To all whom it may concern:

Be it known that I, OLE J. BORGE, a citizen of the United States, residing in Davis township, in the county of Kittson and State 5 of Minnesota, have invented a new and useful Rivet-Feeding Mechanism, of which the following is a specification.

The present invention relates to improvements in rivet feeding mechanisms, one object of the invention, being the provision of 10 a device by means of which rivets may be fed one at a time from a magazine to the female member of a manually controlled or mechanically operated riveting machine, the 15 riveting machine being especially adapted for operating upon the headed tubular rivet generally employed in connection with harness.

A further object of the present invention, 20 is the provision of a rivet feeding mechanism, in which a manually operated mechanism receives and carries a rivet to the female member of the riveting machine, operating means at the mouth of the magazine 25 to permit the next succeeding rivet to be fed by gravity to the lower end of the magazine, there being provided further means actuated upon the return of the rivet carrying mechanism to release such rivet to fall 30 in the latter mechanism so that the next succeeding rivet may be properly delivered.

With the foregoing and other objects in view which will appear as the description proceeds, the invention resides in the combination and arrangement of parts and in the 35 details of construction hereinafter described and claimed, it being understood that changes in the precise embodiment of the invention herein disclosed can be made within 40 the scope of what is claimed without departing from the spirit of the invention.

In the drawings—Figure 1 is a front elevation of the complete machine, the parts being in normal position. Fig. 2 is a top plan view thereof, the carrying portion of 45 the rivet machine being broken away, dotted lines illustrating the rivet feeding or swinging arm when in rivet delivering position. Fig. 3 is an end view of the complete 50 mechanism, the rivet mechanism being shown in section to illustrate the position of the rivet retaining and feeding means disposed therein. Fig. 4 is a section through the rivet carrying member. Fig. 5 is an enlarged 55 detail view of the pivoted member of the rivet carrying arm. Fig. 6 is a view illus- trating the coaction of the same with the female member of the rivet machine.

Referring to the drawings, the numeral 1 designates the base, which has mounted 60 thereon the standard 2 which carries the tubular member 3, the rivet magazine 4 being mounted therein and held in place by means of the screw 5. The magazine 4 is disposed in a vertical position so that the 65 rivets R may be fed therethrough by gravity.

Provided in the lower end of the magazine 4 below the sleeve 3 are the two transverse slots 6 and 7, each of which has disposed 70 therein its respective rivet retaining and feeding blade or members 8 and 9, the same being disposed so as to permit of the proper feeding of the rivets R downwardly and through the outlet end of the magazine 4. 75 These stops 8 and 9 are disposed to engage the heads of the respective rivets and thus maintain them within the magazine, the lower member or blade 8 being operated to release the lowermost rivet for delivery into 80 the recess or receptacle 18' of the swinging arm 16, while the blade 9 maintains the next succeeding rivet to permit the same to fall to be engaged and held by the blade 8, when the arm 16 is initially moved to deliver a rivet. The two blades 8 and 9 are 85 both carried by and movable with the arm or support 10, which arm or support 10 is mounted for limited or oscillatory movement upon the upper end of the vertical post 90 or rod 11. Thus, the blades have a slight movement in the respective slots 6 and 7, so that one blade at a time is projected into the path of the rivet R. Attached to and depending from the sleeve 3 in the path to 95 engage one side of the free end of the arm 10 is a flat spring plate 12 which normally exerts a tension upon the free end of the arm 10 to cause the blade 8 to be disposed within the magazine 4 and below the lowermost 100 rivet R, this being the position of the parts when the elements are in dotted line position as shown in Fig. 2. A second resilient plate 13 is carried by the arm 10 and has its free end disposed in the path of to be 105 engaged by the arm 16 which is carried by the sleeve 14 and mounted for oscillation upon the lower portion of the shaft 11 and for movement independent of the arm 10. Thus when the arm 16 is in the full line position as shown in Figs. 2 and 3, the lower 110 end of the plate 13 is engaged so that the

2
 arm 10 is moved against the tension of the spring 12 and the blade 8 is caused to assume the position as shown in Fig. 3, that is out of the path of the rivet R while the 5 blade 9 is moved into the magazine and consequently into the path of the rivet R so that the lowermost rivet which was released by the blade 8 was delivered to the outlet end of the magazine 4 while the rivet there- 10 about was engaged by the blade 9 and thus consequently held in this position until the arm 16 was caused to be manually operated to assume the dotted line position as shown in Fig. 2. The handle 15 is connected to the 15 sleeve 14, so that the carrying arm 15 may be operated in one direction manually.

Carried in the free end of the arm 16 upon the under side thereof by means of the bolt 17 is the rivet releasing plate or member 18, which constitutes a movable bottom for the rivet receptacle 18', to be operated as will presently appear. One edge of the same, as shown in Fig. 5, is recessed as at 19 while the opposite end is tapered, the 25 purpose of which will presently appear.

Connected to the sleeve 14 in the position opposite to the handle 15 near the lower end thereof, is a pin or stud 20, upon which is slidably mounted one end of the coiled 30 spring 21, the opposite end being connected by means of the fastening device 22 to one free end of the double lever 23, said lever 23 being pivoted at 24 and having connected to its other end, a coiled spring 25, whose opposite terminal is connected to the stud 26 fastened to the base. Thus when the handle 15 is operated manually to place the parts in the position as shown in dotted lines in Fig. 2, the two springs will be placed under 35 tension, so that when the handle 15 is released after having properly positioned the rivets carried in the free end of the arm 16, the springs will operate to return the member 16 to the position as shown in full lines, 40 so that the arm or lever 16 will engage the plate 13 and consequently impart movement to the arm 10 so that the blade 8 will release the lowermost rivet to fall within the receptacle 18' and the blade 9 will be moved 45 across and into the magazine below the next succeeding rivet.

With the present mechanism, the riveting machine 27 is employed the same being provided with the resiliently supported female 55 member 28, which is disposed to coöperate with the male member 30 operated by the coaction of its head 31 with the cam lever 32. The female die 28 of the rivet machine is disposed to engage the outer terminal of the 60 rivet releasing member 18 when the same is moved to the dotted line position in Fig. 2, so that the member 18 is swung on its pivot 17 to permit the rivet carried within the receptacle 18' to be deposited within 65 the female die 28 head downward. When

the member 18 is moved to releasing position, the recess 19 is below the receptacle, thus rendering it necessary to move the member a shorter distance to release the rivet than would be the case if the full 70 width of the member 18 was employed. It will thus be seen with this mechanism, that as the member 16 is moved from the full to the dotted line position in Fig. 2, that the arm 10 will be released to its spring 12 and 75 the blade 9 will be moved to release the next succeeding rivet so that the same will fall upon and be engaged by the blade 8, which was simultaneously placed across the magazine to receive the released rivet. While the 80 member 16 is moved to deliver, as before described, the rivet in the recess or socket 18' is delivered to the female riveting member 28. Upon the release of the handle 15, the 85 spring actuated lever 23 will return the parts to the full line position in Fig. 2, the member 18 engaging the projection 2' of the standard 2 and being moved to close the receptacle 18', while the member 16 engages the plate 13, which transmits motion to the 90 member 10 so as to move the blade 8 outwardly to release the rivet held thereby and to move the blade 9 to engage and hold the next succeeding rivet, such released rivet falling within the recess 18' of the member 16. 95 The tension of the springs 25 and 21 holds the parts in this position with the blade 9 under the lowermost rivet. Thus the arm 10 controls the blades 8 and 9 and consequently the feed and delivery of one rivet 100 at a time. It will thus be seen that with a mechanism of this character, that the rivets are delivered in the proper position to the female member of the riveting machine and that the delivering arm 16 due to the spring 105 return thereof rapidly returns to rivet receiving position and out of the way of the rivet setting plunger 30.

What is claimed is:

1. The combination with a rivet setting 110 machine having a female die, of means for feeding one rivet at a time to the female die, including a rivet magazine, an arm provided with a rivet receptacle disposed for movement to and from the magazine and female die, and a pivoted member carried by the arm for sealing the rivet receptacle thereof, said arm being disposed to coöperate with the magazine to release a rivet therefrom, and to coöperate with the rivet 115 setting machine to release the rivets to the female die.

2. The combination with a rivet setting 120 machine having a frame and a female die, of means for feeding one rivet at a time to the female die, including a rivet magazine, an arm provided with a rivet receptacle disposed for movement to and from the magazine and female die, and a pivoted member carried by the arm for sealing the rivet 125 re-

ceptacle thereof, said arm being disposed to coöperate with the magazine to release the rivet therefrom, and to coöperate with the female die of the rivet setting machine to release the rivet for delivery to the female die.

3. The combination with a rivet setting machine having a female die, of means for feeding one rivet at a time to the female die, including a rivet magazine, two blades mounted in the magazine one above the other, said blades being disposed for movement into the path of the rivets within the magazine to regulate the delivery thereof through the magazine, a swingingly mounted arm provided with a rivet receptacle and disposed for movement to and from the magazine and female die, a spring connected thereto for holding the same below the

magazine, means actuated thereby for operating the blades to cause the delivery of a rivet at a time into the receptacle of the arm when the arm is below the magazine, and a pivoted member carried by the arm for sealing the rivet receptacle thereof, said member being disposed to coöperate with the rivet setting machine when the arm is operated to dispose the receptacle above the female die and be moved from below the receptacle to release the rivet to the female die.

In testimony that I claim the foregoing as my own, I have hereto affixed my signature in the presence of two witnesses.

OLE J. BORGE.
